Inventor:

G. Paltenghi

By C. P. Goepel.

UNITED STATES PATENT OFFICE.

GIOVANNI PALTENGHI, OF BADEN, SWITZERLAND.

DEVICE FOR POINTING WOODEN PENCILS.

Application filed March 28, 1925. Serial No. 18,934.

The devices hitherto used for pointing and sharpening wooden pencils by hand, such as knives, pencil pointers, pencil files, etc., have the disadvantage that the shavings fall down and either remain in the room and litter up the floor, or must be collected in a special receptacle of comparatively large size such as a waste-paper basket; further the shavings soil the hands, clothes, drawings etc., and the air of the room becomes filled with graphite dust.

The object of invention is to eliminate these drawbacks, since the sharpening or pointing tool is completely enclosed and fixed in a box which receives the shavings and is provided with a removable cover.

The drawing shows some practical embodiments of the invention. Fig. 1 is a longitudinal section on the line 1—1 of Fig. 3 looking in the direction of the arrows of a pencil pointer in combination with a pencil file, and Fig. 2 a longitudinal section of a pencil file, of modified form, while Fig. 3 is a cross section of the device as shown in Fig. 2, on the line 3—3 of Fig. 1, looking in the direction of the arrows.

In Figs. 1 and 3 *a* is a casing which may be made out of any suitable material such as transparent celluloid. This casing is tubular and is closed at one end by a cap *f* and at the other end by a cap *k*. Inside of this casing is an ordinary pencil cutter *m* which has a conical bore therein opening through one end to receive the point of the pencil. This bore opens also through one side of the cutter by means of a longitudinal slot and to the outside of the cutter will be fixed a blade *n*, having a sharp edge adjacent said slot. This type of cutter is well known and to sharpen a pencil, the pencil indicated at *h* in broken lines in Fig. 1 is pushed into the open end of this cutter and turned so that the end is shaved by the blade *n*. This cutter is mounted in the cap *f* by being passed through a central hole into the casing and it has a flange *p* at its outer end to engage the exterior surface of the cap *f*.

The inner end of the cutter *n* has a threaded projection *q* which screws into a threaded opening in the sharpener file *b* which has several faces so that the point of a pencil can be rubbed over one of these faces to make the point as fine as desired. A slot *e* in the side of the casing admits the pencil. The cap *k* at the other end of the casing has an opening for a rod or bolt *c*, which screws into a

threaded opening in the other end of the file *b*. This bolt is surrounded by a handle *g* which has a central bore for the bolt. The outer end of this bore may be enlarged and terminate in an inside shoulder *s*, and between the head of the bolt and the shoulder is a spring *d* encircling this bolt *c*. The head of the bolt *c* should be within the handle *g* and the spring acts to force the bolt outward so as to pull upon the file *b* and sharpener *n* and hold the flange *p* against the outside of the collar *f*. The casing *a* may have a base *r*.

In Fig. 2 the sharpener is omitted and the file *b* is engaged by a rod or bolt *c* passing through the cap *f* and encircled by a spring *d*. Between the head of the bolt shown at *i* and the outside of the casing *a* is the washer *w* pressed by the spring *d* against the cap *f*. The other end of the file may have a shank or bolt *o* passing through the cap *k* and made fast to a handle *g*. In this form the point of the pencil is rubbed on the sharpener file *b* by inserting it in the slot *e* in the casing *a*, and the file can be turned to bring any one of its faces into position for operation by means of the handle *g*.

The handle *g* may also serve in the device of Fig. 1 to turn the file *b* and it may be fixed to the bolt *c* for this purpose. Also the file *b* in Fig. 1 might be turned by a tool engaging the head of the bolt *c*.

To open the box and empty the shavings or bits of dust from the point of the pencil, the cover *f* can be taken off against the pressure of the spring *d*. In Fig. 2 the cover *f* may be pulled over against the pressure of the spring *d* and the head *i* may be a nut which can be turned to vary the pressure of the spring *d*. In Fig. 2 the user may take hold of the handle *g* and turn the casing *a* to bring the slot *e* in line with any of the faces of the file *b*.

What I claim is:—

1. A pencil sharpener comprising a casing, having a slot in one wall thereof, a movable rod extending through the end of the casing and outwardly spring held, a sharpener attached to the rod within the casing, and having several working faces so that the sharpener can be actuated to bring any of its faces in position and held to act upon a pencil inserted through the slot in the casing. 100

2. A pencil sharpener comprising a casing, having a slot in one wall, a handle carried by the end of the casing, a movable rod extending through the handle into the casing and 110

outwardly spring held, a sharpener having several working faces, attached to the rod within the casing and adapted to be actuated to bring any of its faces in position and then held by the rod to act upon a pencil inserted through the slot.

3. A pencil sharpener comprising a casing, having a slot in one wall, a handle carried by one end of the casing, a movable rod passing 10 through the handle and outwardly spring held, a sharpener carried adjacent the inner end of the rod within the casing having a series of working faces, and adapted to be turned so that any of the working faces of the 15 sharpener can be brought into position and then held by the rod to act upon a pencil inserted through the slot, and means including a flange engaging the other end of the casing and projecting into the casing and united 20 to the sharpener at the end remote from said rod.

4. A pencil sharpener comprising a casing having a slot in one wall, a handle carried by the end of the casing, a movable rod extending

through the handle into the casing, a file carried by the rod within the casing having a series of working faces adapted to be turned to bring any of its faces in a position to act upon a pencil inserted through the slot. 25

5. A pencil sharpener comprising a casing 30 having a longitudinal opening in one wall, a sharpener rotatably mounted in the casing and having a series of sharpening faces and means for rotating said sharpener so that any one of its working faces may be brought into 35 position to act upon a pencil inserted through the opening in the casing.

6. A pencil sharpener comprising a casing having a slot in one wall thereof, a sharpener rotatably mounted in the casing and adjust- 40 ably spring held, and having a series of sharpening faces, whereby it may be rotated so that any of its faces can be brought into a position to act upon the point of a pencil inserted through the slot. 45

In testimony whereof I have signed my name to this specification.

GIOVANNI PALTENGHI.
